Patented Mar. 28, 1922.

UNITED STATES PATENT OFFICE.

JAMES PETER HARE, OF TODMORDEN, ONTARIO, CANADA.

RAILWAY SWITCH AND CROSSOVER.

1,411,019.

Specification of Letters Patent. Patented Mar. 28, 1922.

Application filed May 27, 1921. Serial No. 472,993.

To all whom it may concern:

Be it known that I, JAMES PETER HARE, of Don Mills Road, Todmorden, in the county of York, Province of Ontario, Canada, a subject of the King of Great Britain, have invented certain new and useful Improvements in Railway Switches and Crossovers, of which the following is a specification.

This invention relates to improvements in railway switches or turn-outs, and my object is to devise a simple and cheap construction in which the expensive "frog" used where one rail crosses the other will be done away with.

I attain my object by means of the construction hereinafter described and illustrated in the accompanying drawings in which—

Fig. 1 is a plan view of a track showing my improved turn-out construction;

Fig. 2 a side elevation of part of a rail showing the guard in a lowered position, its raised position being indicated in dotted lines;

Fig. 3 a section on the line *a—b* in Fig. 2;

Fig. 4 a side elevation of the swinging tongue;

Fig. 5 a cross section through the swinging tongue; and

Fig. 6 an enlarged detail of the means for adjusting the locking means for the swinging tongue.

In the drawings like numerals of reference indicate corresponding parts in the different figures.

1 and 2 are the main line rails and 3 and 4 the turn-out rails. The main line rail 2 and the turn-out rail 3 are, however, cut away where they would normally cross one another. In this cut-away space it is usual to insert a frog, which is a very expensive construction even when such frog has not to be specially made for the position. To avoid this large expense and also to provide a construction which may be easily replaced if worn or damaged, I make this space considerably less in length and provide therein the swinging tongue 5, which may in its simplest form be merely a bar or piece of rail, but which will preferably be formed as follows. 6 is a base provided with inwardly turned flanges 7. Extending down from this base at one end thereof is the pivot pin 8, which extends through a hole in the metal plate 10, which plate will be secured to the ties below the end of the base. Extending down-

wardly from the plate is an integral bushing 9 to give the pivot a good bearing. The end of the pivot pin 8 below the bushing will be provided with a hole 11, through which a pin may be passed to prevent the base being lifted.

Between the flanges 7 on the base is slid the tongue 5, which is usually formed of a piece of rail of sufficient length to fill the space between the parts of the rails 2 and 3. To prevent the rail creeping endwise of the base I provide the members 47 which are bolted to the rail and to the base. To prevent the other end of the base 6 being lifted I provide a plate 12 below the ends of the rails 2 and 3, which plate extends beyond said ends into a slot formed in the end of the base 6. It will thus be seen that the tongue 5 is perfectly free to swing horizontally into alignment with either of the rails 2 or 3, but vertical movement of the tongue relative to the rails is absolutely prevented.

The swinging tongue 5 may be operated by itself, but I prefer, however, to so arrange it that the same mechanism which operates the switch rails 13 and 14 will also simultaneously operate the tongue 5. 15 is the switch stand by means of which the switch rails 13 and 14 are moved in the usual manner through the link 16 and bar 17 which connects the switch rails 13 and 14. To the same end of bar 17 as the link 16 is connected a second link 18, to the other end of which link is pivotally connected one end of a bell crank 19 pivoted on a suitable stationary part. To the other end of this bell crank is pivotally connected a divided rod 20, the parts of which are connected by a turnbuckle 21. The other end of this rod is pivotally connected to the one end of an arm 22, the other end of which is pivoted on a suitable stationary part. On the same pivot as the arm 22 is pivoted a second arm 23, and adjustable means are provided for holding the arms 22 and 23 in spaced relationship to one another, such, for example, as the bolt 24 provided with suitable nuts. The free end of the arm 23 is pivotally connected with one end of a link 25, the other end of which is secured to the swinging tongue 5.

It is advisable, however, to provide means for preventing the operation of the tongue 5 after the end of the train has passed over the points of the switch rails until the end of the train has also passed over the tongue. I use for this purpose the two guard rails

26 which are slidably mounted on supports secured to the outer sides of the rails 1 and 4. These guard rails have recesses in their under sides. When the supports are in these 5 recesses the guard rails occupy the position indicated in full lines in Fig. 2, while when the unrecessed portions of the guard rails rest on the supports, the guard rails occupy the position shown in dotted lines. These 10 guard rails are operated by means of a lever 27, to which is connected one end of a rod 28, the other end of which is pivotally interconnected with the lever 29 pivoted intermediate its ends on a suitable stationary 15 part. To the other end of this lever is pivotally connected a link 30, the other end of which is connected with the guard rail 26 mounted on the track 1. Extending from the lever 29 is an arm 31, to which is pivotally connected one end of a link 32, the other end of which is pivotally connected with one end of a bell crank 33 fulcrumed on a suitable stationary part. The other 20 end of this bell crank 33 is pivotally connected with one end of the link 34, the other end of which is connected with the guard rail 26 on the track 4. As will be seen from Fig. 3, the guard rails 26 when in raised 25 position extend partly over the track. It will thus be seen that should an engine or 30 car be passing over the track that the guard rails cannot be raised. Pivoted on the lever 29 intermediate its pivot and the pivot of the link 30 is a rod 35, the other end of 35 which is slidably supported by a member 36. On the link 25 is mounted the member 37, which is provided with suitable openings into which the end of the rod 35 may project to lock the tongue 5 when it is in 40 alinement with either of the rails 2 or 3.

45 As I prefer to construct my parts so that they may be used no matter at what angle, within certain limits, at which the tracks 2 and 3 may cross one another, I arrange the member 37 so that the spacing of the openings therein may be adjusted. This is illustrated more particularly in Fig. 6, from which it will be seen that a slide 38 is mounted thereon. The member 37 is provided with a hole 39 and a slot 40, while the slide 38 is provided with a hole 41 and slot 42, the hole 39 being opposite the slot 42 and the hole 41 opposite the slot 40. To 50 adjust the slide 38 longitudinally of the member 37, I provide a screw 43 secured in the end of the slide 38 and passing through a hole in the end of the member 37, in which it is held in position as adjusted by means of suitable nuts 44. It will thus be seen 55 that if it is necessary to increase or reduce the distance between the holes 39 and 41, it is merely necessary to adjust the nuts 44 on the screw 43.

60 From the construction described it will 65 be while the wheels of an engine or car are

between the switch rails and tongue, the guards 26 cannot be raised; and while the guard rails are down, the rod 35 is always in engagement in either of the openings 39 or 41, so that the tongue 5 is locked. 70

When the track is clear, the switch standard 15 cannot be operated until the lever 27 is first operated to raise the guard rails and release the rod 35 from engagement with the member 37. 75

It will also be seen that while the guard rails 26 are in raised position that an engine or car cannot be run over the track.

As an additional precaution to prevent the tongue 5 swinging too far in either direction, I provide the block members 45, which are bolted or spiked to a tie underneath. The ends of these block members are shaped to fit between the head and base of the rail and they thus tend to maintain 85 the end of the tongue in proper position. Two further block members 46 are provided at the pivot end of the tongue, and these are also secured and shaped to prevent the tongue from being raised out of position. 90

It will be seen from the foregoing specification that I have devised a construction which will satisfactorily attain the object of my invention as set forth in the preamble of this specification. 95

What I claim as my invention is:—

1. In a railway switch, the combination of a V-shaped rail member; a swinging tongue base pivoted adjacent the point of the V-shaped member; a track member removably supported on said base; a pair of diverging rails one in alinement with each leg of the V-shaped member, the free end of said base with its track being adapted to be brought into alinement with either of the diverging 10 rails; a plate member below the ends of the diverging rails but extending beyond the same, and the base being provided with a slot to receive said extension.

2. In a railway switch, the combination of a V-shaped rail member; a swinging tongue base pivoted adjacent the point of the V-shaped member; a track member slideable on said base; means for preventing endwise movement of the track relative to the base; a pair of diverging rails one in alinement with each leg of the V-shaped member, the free end of said base with its track being adapted to be brought into alinement with either of the diverging rails; a plate member below the ends of the diverging rails but extending beyond the same, and the base being provided with a slot to receive said extension. 11

3. In a railway switch and crossover, the combination of a pair of outer rails; a V-shaped rail member between said outer rails; a swinging tongue pivoted adjacent the point of the V-member; a pair of diverging switch rails one in alinement with each leg of the 11

V-shaped member, the free end of the tongue being adapted to be brought into alinement with either of the switch rails; means for simultaneously swinging the switch rails and 5 tongue; means for locking the aforesaid means from movement; supports secured to the outer rails; guards longitudinally slideable on the supports, the said guards having recesses formed in their under side; and 10 means for simultaneously releasing the locking means and raising the guard rails.

4. In a railway switch and crossover, the combination of a pair of outer rails; a V-shaped rail member between said outer rails; 15 a swinging tongue pivoted adjacent the point of the V-member; a pair of diverging switch rails one in alinement with each leg of the V-shaped member, the free end of the tongue being adapted to be brought into alinement with either of the switch rails; and 20 means for simultaneously swinging the switch rails and tongue; means for locking the aforesaid means from movement, said means including a pair of members, one slideable relative to the other, and each having a pair of openings therein, one opening being of greater length than the other, the longer opening in one member being opposite the shorter opening in the other; and means for preventing the release of the locking means while the wheels of a train are on 25 a switch rail, the first mentioned means being adjustable to regulate the swing of

the tongue and the locking means being also adjustable to agree with the first mentioned means.

5. In a railway switch and crossover, the combination of a pair of outer rails; a V-shaped rail member between said outer rails; a swinging tongue pivoted adjacent the point of the V-member; a pair of diverging 35 switch rails one in alinement with each leg of the V-shaped member, the free end of the tongue being adapted to be brought into alinement with either of the switch rails; means for simultaneously swinging the 40 switch rails and tongue; means for locking the aforesaid means from movement, said means including a pair of members, one slideable relative to the other, and each having a pair of openings therein, one opening being of greater length than the other, the longer opening in one member being opposite the shorter opening in the other; and means for preventing the release of the locking 45 means while the wheels of a train are on a switch rail.

Signed at Toronto, Can., this 12th day of May, 1921.

JAMES PETER HARE
